E. S. HARTSON

UNDERREAMER

Filed April 11, 1927

UNITED STATES PATENT OFFICE.

EARL S. HARTSON, OF LOS ANGELES, CALIFORNIA.

UNDERREAMER.

Application filed April 11, 1927. Serial No. 182,723.

My invention relates to an underreamer that is particularly designed for use in oil wells for reaming or enlarging that portion of the drill hole below the casing in order that the latter may be lowered into the well as the drilling and underreaming operations proceed.

The principal object of my invention is to generally improve upon and simplify the construction of the existing forms of underreamers, and particularly the underreamer forming the subject matter of a co-pending application for U. S. Letters Patent filed by me February 26, 1927, Serial No. 171,212.

Further objects of my invention are to provide simple and efficient means for effecting a positive outward or expanding movement of the bits or cutter blades to the underreamer and, likewise, for positively reTRACTING or drawing said bits or cutter blades into the shell or housing, which bit actuating means is operated by a tubular mandrel having right and left hand threads and with which cooperates a pair of nuts or bushings and a conical member, and, further, to provide automatically acting means for alternately effecting engagement between the nuts or bushings and the conical member to elevate and lower the same within the housing of the underreamer and consequently project and retract the bits that are associated with the conical member, and which automatic actuation of the parts is accomplished without the necessity of rotating the threaded mandrel which forms a part of the drill tube anti-clockwise, or toward the left hand.

With the foregoing and other objects in view, my invention consists in certain novel features of construction and arrangement of parts that will hereinafter be more fully described and claimed and illustrated in the accompanying drawing, in which—

Fig. 1 is a vertical section taken lengthwise through the center of an underreamer constructed in accordance with my invention and showing the bits or cutter blades in their fully expanded positions.

Fig. 2 is an enlarged horizontal section taken on the line 2—2 of Fig. 1.

Fig. 3 is a horizontal section taken on the line 3—3 of Fig. 1.

Fig. 4 is a detail section taken on the line 4—4 of Fig. 1.

Fig. 5 is a section taken on the line 5—5

of Fig. 1 and looking upwardly against the underside of the conical member that actuates the bits.

Referring by numerals to the accompanying drawings, which illustrate a practical embodiment of my invention, 10 designates a hollow cylindrical shell that forms a housing for the parts of the underreamer and extending axially therethrough, is a tubular mandrel 11 that is provided with externally arranged quick acting right and left hand threads 12 and 13, respectively.

The ends of this threaded mandrel are arranged for rotation in bushings 13^a that are seated in the ends of shell 10 and the upper end of said mandrel is connected to the lower end of the drill tube T. The lower end of the mandrel below the housing 10 is connected to a sub or to the upper end of the body of a drill.

Arranged for vertical movement within 75 the housing 10, is a tapered or conical member 14 provided with an axially arranged bore 15 for the accommodation of the threaded mandrel and mounted to rotate freely in the upper end of the bore 15, is 80 a nut or bushing 16 having internally arranged short left hand threads 17 that engage the left hand thread 13 on mandrel 11.

Carried by the nut or bushing 16, is a vertically disposed pin 18 that is normally 85 forced upward by a spring 19 and the lower end of this pin that projects below the nut or bushing is adapted to engage against the shoulder 20 that is formed at the end of a concentric groove 21, and which latter is 90 formed in the top of the conical member 14. This groove 21 gradually increases in depth toward the shoulder 20.

Formed through the wall of mandrel 11, just below the upper one of the bushings 13, 95 is an aperture 22 within which is arranged a check valve 23 carrying a pin 24 that normally projects beyond the face of the mandrel 11 and arranged on this pin behind the valve 23, is an expansive coil spring 25 100 that tends to move the valve inwardly so as to close the inner end of the aperture 22. During drilling operations, the pressure of the water and mud that constantly flows through the drill tube T and mandrel 11 105 exerts pressure on check valve 23 to hold the same off its seat at the inner end of the aperture 22 and thus the pin 24 projects be-

yond the surface of the mandrel and forms a stop to limit the upward movement of the nut or bushing 16.

Loosely mounted in the lower end of the axial bore 15, is a nut or bushing 26 having internal threads 27 that engage in the right hand thread 12 on mandrel 11 and carried by the lower portion of the nut or bushing, is a disk 28 through which passes a pair of pins 29. Arranged in the disk 28 beneath these pins, are coil springs 30 that normally exert upward pressure on said pins and connected to the lower ends of said pins below the disk 28, is a larger disk 31 having a centrally arranged opening 32 for the accommodation of mandrel 11.

Formed on the interior of the wall of shell 10, are lugs 33 that are adapted to serve as stops to limit the upward movement of the disk 31 and said stops being located so that the disk 31 engages against said stops just before the upper end of pin 18 in nut or bushing 16 strikes against the upper end of the housing 10.

Formed in the underside of conical member 14, are concentric arcuate grooves 34, each of which gradually decreases in depth toward one end and formed at the deepest end of each groove, is a shoulder 35 that is adapted to be engaged by the upper portion of one of the pins 29.

Formed in the outer surface of conical member 14, are two or more longitudinally disposed slots 36 that are substantially T-shaped in cross section and in which are arranged for sliding movement the T-shaped inner ends of bits or cutters 37. These bits or cutters are arranged for sliding movement through slots or openings 38 that are formed in the wall of housing 10.

In the operation of my improved underreamer and before the same is connected to the drill tube and lowered into the well, the mandrel 11 is rotated so as to permit the conical member 14 to move downward within the shell 10 to its lower limit of movement and, as a result of this downward movement of the conical member, the bits or cutters 37 will be retracted or drawn into the shell or housing, due to the engagement between the inner ends of said bits and the T-shaped slots in said conical member.

When the bits are properly positioned within the housing, their outer edges lie flush with or slightly below the outer surface of the housing and thus, as the underreamer is lowered into the well casing, there will be nothing to interfere with its free downward movement. The underreamer is now connected to the well tubing T and, as the latter is lowered, the underreamer will move downward until it is positioned just below the lower end of the casing.

The drill tube is now rotated in the usual manner clockwise, or toward the right hand,

and the engagement of the threads of nut or bushing 26 with the right hand thread 12 on mandrel 11 will cause said nut or bushing to move upwardly until the upper ends of pins 29 pass into the concentric arcuate groove 34 and finally engage against the shoulders 35 at the ends of said grooves and, following this engagement, which is in effect the locking of the nut or bushing to the conical member, said nut or bushing will cease to rotate, but, owing to the rotation of the mandrel, said nut and the conical member 14 to which it is locked, will be elevated on the mandrel and as such movement takes place, the bits 37 will be expanded or forced outward through the openings 36 in housing 10.

As the conical member 14 reaches its upper limit of movement within the housing, the upper end of nut or bushing 16 will engage against projecting pin 24, which functions as a stop and which pin is held in its projected position by the pressure of the mud and water circulating through the drill tube and mandrel and, following this engagement of the upper nut against pin 24, all parts of the underreamer will rotate with the drill tube and mandrel as an integral structure and the projected or expanded bits 37 will cut and ream away the earth below the lower end of the casing so as to permit the latter to be lowered after the reaming operations.

At the completion of the underreaming operations and when it is desired to retract the cutters so as to lower the underreamer or elevate the same through the casing, the pressure on the mud and water that is circulating through the drill tube is relieved, whereupon spring 25 will act to seat valve 23 thereby withdrawing pin 24 from its position above nut 16 and, following this action, the conical member 14 will move upward a slight distance, or until the upper end of pin 18 strikes against the upper end of the housing 10, which action moves said pin downward against the pressure of its spring and the lower end of said pin enters groove 21 and engages against the shoulder 20 at the end thereof.

This action is in effect a locking of the nut 16 to the upper end of conical member 14 and simultaneous with such action, disk 31 engages stop lugs 33 and, as the conical member continues to move a short distance upward to its limit of upward movement, the pins 29 will be withdrawn from the grooves 34, thereby unlocking nut 26 from the lower end of conical member 14 and said nut, by its own weight and the weight of the disk 31, will immediately move downward on mandrel 11 to the lower portion of the chamber within housing 10.

The drill tube T continues to rotate toward the right hand and the engagement of

the threads 17 on nut 16 with the left hand thread 13 on the mandrel will cause said nut to move downwardly on the mandrel, thereby forcing conical member 14 downward and consequently retracting or withdrawing the bits or cutters 37 into the housing.

Thus it will be seen that I have provided an underreamer having a plurality of radially movable bits or cutters and which latter are positively expanded or moved outward and likewise positively retracted or drawn inward, such action being accomplished through the medium of a vertically 15 conical member that has sliding connections with the bits or cutters and which conical member is caused to move vertically within the housing by the alternate automatic locking of nuts or bushings to the ends of said conical member, and which nuts or bushings have engagement with the right or left hand threads of a tubular mandrel, the latter forming a part of the drill tube.

It will be understood that minor changes 25 in the size, form and construction of the various parts of my improved underreamer may be made and substituted for those herein shown and described without departing from the spirit of my invention, the scope 30 of which is set forth in the appended claims.

I claim as my invention:

1. In an underreamer, a housing, a tubular mandrel extending axially through said housing, said mandrel having right and 35 left hand threads, a conical member arranged within the housing, cutter blades arranged for movement through the wall of the housing, the inner portions of which cutter blades have inter-engagement with said conical member, nuts loosely mounted in the ends 40 of said conical member, one of which nuts engages in the right hand thread of the mandrel, the other nut having engagement with the left hand thread of the mandrel and 45 automatically acting means for effecting an alternate locking of said nuts to the ends of said conical member.

2. In an underreamer, a housing, a tubular mandrel extending axially through said 50 housing, said mandrel having right and left hand threads, a conical member arranged within the housing, cutter blades arranged for movement through the wall of the housing, the inner portions of which cutter blades have inter-engagement with said conical member, nuts loosely mounted in the ends 55 of said conical member, one of which nuts engages in the right hand thread of the mandrel, the other nut having engagement with the left hand thread of the mandrel, automatically acting means for effecting 60 an alternate locking of said nuts to the ends of said conical member and a pressure actuated check valve arranged in the upper portion of the mandrel and functioning as a

stop to limit the upward movement of the nut at the upper end of said conical member.

3. In an underreamer, a housing, a conical member within said housing, cutter blades arranged for movement through openings in the wall of said housing, the inner portion of which cutter blades have inter-engagement with said conical member, a tubular mandrel extending axially through said housing and conical member, said mandrel having right and left hand threads and means arranged at the ends of said conical member and having engagement respectively with the right and left hand threads of the mandrel for alternately locking said 70 conical member to said mandrel to effect vertical movement of said conical member within said housing.

4. In an underreamer, a housing, a conical member within said housing, cutter 85 blades arranged for movement through openings in the wall of said housing, the inner portion of which cutter blades have inter-engagement with said conical member, a tubular mandrel extending axially through 90 said housing and conical member, said mandrel having right and left hand threads, means arranged at the ends of said conical member and having engagement respectively with the right and left hand threads of the 95 mandrel for alternately locking said conical member to said mandrel to effect vertical movement of said conical member within said housing and a pressure actuated check valve in the upper portion of the mandrel, 100 which check valve functions as a stop to limit the upward movement of the conical member within said housing.

5. In an underreamer, a housing, a conical member within said housing, cutter 105 blades arranged for movement through openings in the wall of the housing, the inner ends of which cutter blades have sliding engagement with said conical member, a tubular mandrel extending axially through 110 said housing and conical member, nuts loosely mounted in the ends of the conical member and having threaded engagement respectively with the right and left hand threads of the mandrel, the ends of the conical member being provided with shoulders and spring-held pins carried by said nuts and adapted to engage the shoulders in the ends of said conical member to lock said nuts to 115 said conical member.

6. In an underreamer, a housing, a conical member arranged therein, cutters arranged for operation through the wall of said housing, the inner ends of which cutters having sliding engagement with said conical member, a tubular mandrel extending axially through said housing and conical member, which mandrel is arranged for rotation in the ends of the housing, said mandrel having right and left hand threads, nuts 125 130

loosely arranged in the ends of said conical member and having engagement respectively with the right and left hand threads of the mandrel, means for automatically locking the lower one of said nuts to the lower end of said conical member when the latter is in the lower portion of the housing and means for automatically locking the upper one of said nuts to the upper end of said conical member when the latter is in the upper portion of said housing.

7. In an underreamer, a housing, a conical member arranged therein, cutters arranged for operation through the wall of said housing, the inner ends of which cutters having sliding engagement with said conical member, a tubular mandrel extending axially through said housing and conical member, which mandrel is arranged for rotation in the ends of the housing, said mandrel hav-

ing right and left hand threads, nuts loosely arranged in the ends of said conical member and having engagement respectively with the right and left hand threads of the mandrel, means for automatically locking the lower one of said nuts to the lower end of said conical member when the latter is in the lower portion of the housing, means for automatically locking the upper one of said nuts to the upper end of said conical member when the latter is in the upper portion of said housing, and means for automatically releasing the locking means between the lower one of said nuts and the lower end of said conical member when the locking means between the upper one of said nuts and the upper end of said conical member is engaged.

In testimony whereof I affix my signature.
EARL S. HARTSON.
